UNITED STATES PATENT OFFICE.

WILLIAM ZEEDYK, OF PATERSON, NEW JERSEY, ASSIGNOR TO BENJAMIN EASTWOOD COMPANY, OF PATERSON, NEW JERSEY, A CORPORATION OF NEW JERSEY.

BOX-OPERATING MECHANISM.

1,339,999.

Specification of Letters Patent. Patented May 11, 1920.

Application filed May 5, 1919. Serial No. 294,927.

To all whom it may concern:

Be it known that I, WILLIAM ZEEDYK, a citizen of the United States, residing at Paterson, in the county of Passaic and State 5 of New Jersey, have invented certain new and useful Improvements in Box-Operating Mechanisms, of which the following is a specification.

My present invention is an improvement 10 in box operating mechanisms for looms of that kind which is characterized by the use of intermeshing gears. The invention results in a much simpler and more substantial and durable construction than these 15 mechanisms have heretofore possessed, and in addition it makes it possible to equip an old loom with a box operating mechanism with slight changes in the loom itself, and it involves certain other and special ad- 20 vantages, namely, in respect to the mounting of the gears, the timing of the shifting of the boxes with reference to the picking motion, and the mounting of the box structure on the box operating rod.

25 In the drawings,

Figure 1 is a side elevation of my improved mechanism in position on a loom;

Fig. 2 is a rear elevation thereof on a larger scale;

30 Fig. 3 is a plan of the box operating lever;

Fig. 4 shows the connection between the box structure and its operating rod;

Fig. 5 is a side elevation, partly in section, of the pair of gears and the holding 35 pawl for the driven gear;

Fig. 6 is a sectional view of the driven gear, showing the manner of connecting the pitman 12 thereto;

Fig. 7 is a sectional view illustrating the 40 driving gear and its mounting; and

Figs. 8 and 9 are a side and a rear elevation of the main bracket for supporting the moving parts.

In the drawings *a* is the frame of the loom 45 and *b* the tappet shaft from which the picker sticks are actuated, the same being rotated at constant speed by any suitable means (not shown). *c* designates the boxes movable rectilineally up and down in the 50 guideways *d* in the batten *e* in the usual manner, and *f* is the box operating rod which (containing some well known means, as *f'*, not necessary to describe herein, for allowing the effective length of the rod to change 55 should the boxes become jammed, as by an

improperly boxed shuttle) is connected at its lower end with one end of the box operating lever *g*. The center of motion of the boxes in moving back and forth with the batten (to wit, the shifting axis at the point where 60 the rod *f* is connected with the lever *g*) is generally not coincident with the center of motion of the batten (to wit, the shaft *h*, which affords the axis of movement of the lay swords *i* carrying the batten), and on 65 this account in the usual construction the rod *f* is allowed to yield or flex somewhat, which causes a binding of the boxes in their guideways, unless of course the boxes are somewhat loose in their guideways, either of 70 which expedients is obviously very undesirable. Again, since the boxes in the usual construction are rigidly secured to the upper end of the rod, a jam caused by the box structure moving when a shuttle is only 75 partly housed will result in such a bending of the parts that one end of the boxes will be higher than the other, that is, the boxes will not remain truly horizontal, which is necessary in order to direct the flight of the 80 shuttle in strict parallelism with the lay or batten and insure against its being thrown out of the loom. In order to overcome this difficulty I provide the connection between the boxes and the rod *f* shown in Figs. 1 and 85 4. That is: a bracket *j* is secured to the under side of the boxes, and the upper end of the rod *f* has a head *k*, and connecting the bracket *j* and head *k* is a coupling *l* which is pivoted in the bracket *j* on an 90 axis *m* extending transversely of the loom and in the head *k* on an axis *n* transversely of the axis *m*, the axis *n* being afforded by a bolt having a nut *o* to clamp the head *k* fast to the coupling. By this 95 connection the rod *f* and boxes are connected on a pivot *m* which allows the boxes to move up and down in their guideways in a perfect rectilineal path, without lost motion in the guideways and without flexing of the rod 100 in the back and forth motion of the boxes with the batten; and if a jam occurs and results in disturbing the alinement of the boxes the proper adjustment can be effected at *n*, *o*, it being understood that the nut *o* 105 is usually screwed up tight so that the coupling maintains a fixed relation to the rod.

A bracket *p* is bolted to the loom frame *a* and in a horizontal slot *q* of this bracket is adjustably arranged the stud *r* which affords 110

a fulcrum for the lever *g*. In this bracket, in arms *s* projecting therefrom is fulcrumed a lever structure including a horizontal shaft *t*, an arm *u* fixed to the shaft and adapted to be connected to a dobby or equivalent by the wire *v*, and a shifting fork *w* which latter will be described in detail; the lever referred to is normally held in the position shown in Fig. 2 by a spring *x* connecting one arm of the fork *w* with the bracket *p*.

The driven gear member *y* is journaled on a stud *z* projecting from the bracket *p*. It has sets of segmental peripheral teeth (in the present case two) the first tooth 2 in each set being appreciably thicker and more substantial than the other teeth; the two sets of teeth are in the same plane. Formed integral with and on the back of the gear is a stop wheel 3 having diametrically opposite arc-shaped recesses 4. The front of the gear has a radial housing 5 formed with a radial outside slot 6, the housing and slot being open at the periphery. The slotted housing receives the headed end of a bolt 7 on which are a bushing 8 provided with a flange or head 9 at its inner end, a washer 10 to bear against the outer end of the bushing and a nut 11, the parts 7 to 11 forming in effect a wrist-pin which may obviously be adjusted radially of the gear. The bushing forms a bearing for the upper end of a pitman 12 connected to the rear end of the lever *g*.

The driving gear 13 has a set of peripheral teeth extending only part way around its periphery, the first tooth 14 being thicker and more substantial than the others; the remainder of the gear periphery is made neutral, as by being within the circle occupied by the toothed portion. The gear has a forwardly projecting hub 15 provided with a peripheral groove 16, and its bore is formed with a longitudinal groove 17. The axial support for the gear is a sleeve 18 which is slipped onto the projecting end of the tappet shaft *b* and may be rotatively adjustably secured thereto by a set screw 19 preferably tapped into an enlargement or hub 20 at the inner end of the sleeve. Set in the sleeve is a key or feather 21 engaged in the groove 17 of the gear, which is thus splined to the sleeve, and on the outer end of the sleeve is secured a collar 22, said collar and the hub 20 being spaced at such a distance that when the gear 13 abuts the hub it is in the same plane with and will intermesh with the gear *y* and when it abuts the collar it is clear of the gear *y* and may rotate without actuating it.

The aforementioned shifting fork *w* engages with its pins 23 in the groove 16 of gear 13 and in the preferred construction this fork is formed with its fork proper 24 pivoted in a socket 25 of the lever structure

u, t, w so that the fork proper may turn on an axis radial with respect to the fulcrum of said lever structure; this insures the pins 23 engaging without undue binding and hence without undue wear in the groove 16 of gear 13.

Between rotary impulses imparted to the gear *y* by gear 13 the former should be held stationary. To this end, a holding pawl is provided, the same consisting of a lever 26 fulcrumed in the bracket *p* and equipped with the roller 27 which bears against the periphery of the stop wheel 3 of gear *y* and at the holding periods engages in the recesses 4 of the stop wheel, the pawl being held against the periphery of the stop wheel by a spring 28.

Subject to the spring *x* the gear 13 normally stands out of position to intermesh with and actuate the gear *y*, in consequence of which the boxes remain stationary. Upon the "call" of the dobby, however, and through the medium of the lever structure *u, t, w*, the gear 13 is from time to time shifted into the plane of the gear *y*, so that on every rotation of the sleeve 18, and consequently of gear 13, with the shaft *b* gear 13 will turn gear *y* a half revolution, thus moving the boxes up or down through the connections described, leaving them at a standstill between movements.

My box operating mechanism is practically wholly self-contained, so that to equip a loom therewith it is only necessary to bolt the bracket *p* to the loom frame and secure the sleeve 18 carrying the gear 13 on shaft *b*. As to this sleeve it serves both as a means to allow the gear 13 to be shifted longitudinally of the shaft while fixed to turn therewith and as a means to rotatively adjust the gear on the shaft, whereby to time the movements of the boxes with the picking motion of the loom so that the two will occur in proper synchrony.

Collar 22, which affords a stop device for gear 13 under the pressure of spring *x*, may be shifted and secured inward so as to hold gear 13 in the same plane as gear *y*, against the tension of spring *x*, so that the shifting of the boxes will continue regularly, which is desirable in the weaving of certain fabrics.

In box operating mechanisms of this class the driven gear (or a part of the same) has heretofore been the shiftable one. In order to obtain the connection with the lever *g* or equivalent this led to complications and to weakness of structure. In my arrangement the shifting member is the driving one, so that the mechanism is simplified and becomes more substantial and durable.

Having thus fully described my invention, what I claim and desire to secure by Letters Patent is:

1. In combination, a supporting structure

including a rotary shaft, an axial supporting member rotatively adjustable on the shaft, a shiftable shuttle box structure, means to impart shifting motion from said 5 rotary element to the box structure including a driven gear journaled in the supporting structure on an axis parallel with said shaft and a driving gear splined on said axial supporting member and shiftable 10 thereon into and out of the plane of the driven gear and adapted to mesh with the latter when in said plane, and means to shift said driving gear back and forth.

2. In combination, a supporting structure 15 including a rotary element, a shiftable shuttle box structure, means to impart shifting motion to said box structure including a pair of gears having parallel axes and arranged one on said element and shiftable thereon 20 into and out of the plane of the other gear and adapted to mesh therewith when in said

plane, a stop device to limit the shifting movement of the shiftable gear in one direction, said stop device being arranged on said element and adjustable thereon in the 25 opposite direction, and yielding means normally urging said shiftable gear toward the stop device.

3. In combination, with the up and down rectilinear guideways of a batten structure, 30 a shuttle box structure arranged and movable in said guideways, a box operating rod extending upwardly, and a pivotal coupling between the upper end of the rod and said box structure having its pivoting axis ex- 35 tending transversely of the loom, said coupling being adjustable on the rod on an axis extending substantially from front to rear of the loom.

In testimony whereof I affix my signature. 40

WILLIAM ZEEDYK.
